UNITED STATES PATENT OFFICE.

LE ROY W. FAIRCHILD, OF NEW YORK, N. Y.

DESIGN FOR A PENCIL-CASE.

SPECIFICATION forming part of Design No. 12,436, dated August 30, 1881.

Application filed April 5, 1881. Term of patent 7 years.

To all whom it may concern:

Be it known that I, LE ROY W. FAIRCHILD, of New York city, county and State of New York, have invented and produced a new and original Design for a Case for Pencils and Similar Implements, of which the following is a specification, reference being had to the accompanying photograph, forming part thereof.

The accompanying photograph is a side elevation of a case illustrating my design.

The leading feature of my design consists in a raised figure of a fish or of fishes on the exterior surface of the case, as indicated by the letter D on the photograph.

In the illustration I have represented two fishes arranged longitudinally on the case; but the number may be more or less, as may be desired, or according to the size of the case, the figure of the fish constituting the distinguishing feature of the design.

In the illustration I have shown a line as being arranged spirally around the case, as indicated by the letter C; but instead of the line

a vine or wreath may be arranged in the same manner without changing the design.

The figures of the fish and the line are raised on the surface of the case, and are usually made of a different kind of metal from the case, or of a different shade of the same metal, which imparts to the article a very rich and ornamental appearance, and renders the design more prominent.

A ring, B, is secured to the case for the purpose of attaching it to the watch chain or guard, as is usual with this class of articles; but this ring forms no part of my present design.

What I claim is—

The design for a case for pencils and similar implements, consisting of the fish or fishes D and the line C, applied to the body of the case, substantially as herein described.

LE ROY W. FAIRCHILD.
